FISH LURE SAVING DEVICE

Elmer L. Freeman, P.O. Box 213,
Shawnee, Okla. 74801

Filed Aug. 28, 1972, Ser. No. 283,907

Term of patent 14 years

Int. Cl. D22—05

U.S. Cl. D22—31

FIG. 1 is a partial side view of the fish lure saving device of this invention,

FIG. 2 is a perspective view of the device of the invention, portions broken away denoting indeterminate length,

FIG. 3 is a top view taken along line 3—3 of FIG. 1,

FIG. 4 is a bottom view of the device,

FIG. 5 is an end view of the device, and

FIG. 6 is a view of the other end of the device.

FIGS. 1, 5 and 6 are shown with the upper handle portion omitted for convenience of illustration.

I claim:

The ornamental design for a fish lure saving device, substantially as shown and described.
